(57) **CLAIM**

The ornamental design for holding cabinet for serving precooked food products, as shown.

DESCRIPTION

FIG. 1 is a perspective view of a holding cabinet for serving precooked food products, which depicts a bottom right portion of the holding cabinet in an opened position, according to an embodiment of the design.

FIG. 2 is a right side view of the holding cabinet for serving precooked food products of FIG. 1, according to an embodiment of the design.

FIG. 3 is a left side view of the holding cabinet for serving precooked food products of FIG. 1, according to an embodiment of the design.

FIG. 4 is a rear view of the holding cabinet for serving precooked food products of FIG. 1, according to an embodiment of the design.

FIG. 5 is a front view of the holding cabinet for serving precooked food products of FIG. 1, which depicts the bottom right portion of the holding cabinet in a closed position, according to an embodiment of the design.

FIG. 6 is a top view of the holding cabinet for serving precooked food products of FIG. 1, according to an embodiment of the design; and,

FIG. 7 is a bottom view of the holding cabinet for serving precooked food products of FIG. 1, according to an embodiment of the design.

The broken line showing of environment in the drawings is for illustrative purposes only and forms no part of the claimed design.
